(57) **CLAIM**

The ornamental design for a data cable, as shown and described.

DESCRIPTION

FIG. 1 is a perspective view of a data cable, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.

The pair of parallel dash-dot-dash broken lines show a symbolic break in the data cable. The appearance of the break lines and any portion between the parallel dash-dot-dash lines forms no part of the claimed design.
